Inventor
Alex Pritchard.
Attorney G. Fountain
By his

UNITED STATES PATENT OFFICE.

ALEXANDER PRITCHARD, OF EVERGREEN, NEW YORK.

HORSESHOE ATTACHMENT.

Application filed October 14, 1920. Serial No. 416,998.

To all whom it may concern:

Be it known that I, ALEXANDER PRITCHARD, a citizen of the United States, and resident of Evergreen, in the county of Kings and State of New York, have invented certain new and useful Improvements in Horseshoe Attachments, of which the following is a specification.

This invention relates to attachments for horseshoes, and has for its principal object the provision of means for preventing a horse from slipping on icy or other smooth surfaces; further objects being to provide a device of this character which may be securely and quickly attached to a horseshoe, and which comprises few parts of simple, durable and inexpensive construction.

In carrying out my invention I employ a clamping device which may be readily attached to and removed from a horseshoe, and which comprises a rear clamping member having transversely extended heel-calk, a detachable toe-calk, and novel means for adjusting the device, all as hereinafter fully described and specifically set forth in the appended claims.

In the accompanying drawings forming part of this specification, Figure 1 is a plan view of an embodiment of my invention showing its correlation with a horseshoe, said shoe being shown by dotted lines;

Fig. 2 is a side view; and

Fig. 3 is a rear view of one of the clamping members.

In the example of my invention illustrated by the drawings, 1 indicates a forward clamping member and 2 a rearward clamping member.

The forward member 1 constitutes a malleable metal plate 3, having integrally-formed forwardly-extended tapered prongs 4, which are adapted, when the device is attached to a horseshoe, to be bent upwardly over the toe of the shoe and against the horse's hoof, as shown by dotted lines 4^a, Fig. 2, whereby said clamping member may be securely retained.

On the bottom of the plate 3 is a dovetailed groove 5, formed by means of transversely extended parallel flanges 6, which are made integral with the plate 2; and extended through this groove and transversely across the plate 2 is a detachable toe-calk 7, which may be removed and replaced

by a new calk when worn down to impracticable proportion.

The rearward clamping member 2 embodies a strut 8 and a heel-calk 9 which extends transversely across the bottom of the shoe, said strut being provided with end recesses 10 for engaging the end parts of the heel of the shoe, as shown by Fig. 1.

As a means for connecting the members 1 and 2, I employ a rod 11, having on its forward end an approximately S-shaped coupling 12, which passes through a slot 14 of the plate 3, the lower loop 13 of said coupling engaging beneath the plate 3 and partly around its rounded rearward end, and the upper member 15 bearing over the rearward part of the toe of the horseshoe.

The rear end of the rod 11 is screw-threaded and it passes through an opening 16 of the strut 8 and is fixed thereto by means of adjustable nuts 17 and 18, which are in threaded engagement with the rod 11, whereby the device may be securely adjusted to a horseshoe and maintained in proper fixed relation therewith.

In the operation and use of the invention, the clamping members 1 and 2 are spaced apart and brought into clamping engagement with a horseshoe (shown in dotted outline in Figs. 1 and 2), the nuts 17 and 18 are then adjusted to fix the parts in proper correlation, after which the prongs 4 are bent upwardly until they contact over the toe of the horseshoe and the front of the horse's hoof, thus securely fixing the forward clamping member to prevent its accidental downward swing; and when it is desired to remove the device from the horseshoe the prongs 4 may be straightened or flattened out, whereby the front clamping member may be swung downwardly on the curved lower loop of the coupling 12.

It is manifest that my improved device may be readily attached to and detached from a horseshoe, and it constitutes an efficient non-slipping device which is susceptible of attachment to horseshoes of various proportions.

I do not wish to be understood as confining myself to the specific details of mere mechanical construction and form of the parts as disclosed by the embodiment of my improvements herein shown and described, as under the spirit and scope of my inven-

tion I believe that I am entitled to employ slight variations of construction.

Having thus described my invention, what I claim as new and desire to secure by Letters Patent, is:

1. An antiskid attachment for horseshoes, comprising a strut having end recesses, a transverse opening, and a heel-calk, and a front clamping member constituting a malleable plate having a toe-calk, forwardly extended prongs, and a lateral slot, and a rod having at its forward end a hook for engaging said slot, said rod at its rear end engaging through the opening of said strut, and means for adjustably fastening said rod to said strut.
2. An antiskid attachment for horseshoes, comprising a strut having end recesses, a

transverse opening leading therethrough, and a heel-calk on the bottom thereof, and a front clamping member constituting a malleable plate having a dovetailed groove in its bottom, and a detachable toe-calk within said groove, said plate having tapered prongs extending forwardly therefrom and a lateral slot in its rearward end part, and a rod having at its forward end an approximately S-shaped coupling, said coupling engaging through said slot, said rod having a screwthreaded rear end, and nuts engaging said threaded part and adapted to fix said rod to said strut.

Signed at Ridgewood, in the county of Queens and State of New York, this 27th day of Sept., A. D. 1920.

ALEXANDER PRITCHARD.
